(57) **CLAIM**

The ornamental design for a hook, as shown and described.

DESCRIPTION

FIG. 1 is a front view of a first embodiment of a hook and a second embodiment of a hook showing our new design, in the environment of a wall mountable rail system.

FIG. 2 is a side view of the first embodiment of the hook of FIG. 1, in the environment of the wall mountable rail system, the other side being a mirror image thereof.

FIG. 3 is a side view of the second embodiment of the hook of FIG. 1, in the environment of the wall mountable rail system, the other side being a mirror image thereof.

FIG. 4 is a front view of the first embodiment of the hook of FIG. 1.

FIG. 5 is a rear view of the first embodiment of the hook of FIG. 4.

FIG. 6 is a side view of the first embodiment of the hook of FIG. 4, the other side being a mirror image thereof.

FIG. 7 is a top view of the first embodiment of the hook of FIG. 4.

FIG. 8 is a bottom view of the first embodiment of the hook of FIG. 4.

FIG. 9 is a front view of the second embodiment of the hook of FIG. 1.

FIG. 10 is a rear view of the second embodiment of the hook of FIG. 9.

FIG. 11 is a side view of the second embodiment of the hook of FIG. 9, the other side being a mirror image thereof.

FIG. 12 is a top view of the second embodiment of the hook of FIG. 9; and,

FIG. 13 is a bottom view of the second embodiment of the hook of FIG. 9.

The broken lines in the drawings represent unclaimed environmental subject matter.
